STRAW PACKAGING MACHINE

Salvatore A. Franco, Medford Station (Patchogue), N. Y., assignor to Diamond Straw & Machine Corporation, New York, N. Y., a corporation

Application September 26, 1947, Serial No. 776,350

3 Claims. (Cl. 93—3)

1

This invention relates generally to article-packaging machines, and more particularly to machines which package drinking straws for sanitary individual use.

Prior machines of this type are known which pack one or two drinking straws in a tube-like wrapper of paper or the like and seal the ends of the wrapper. These prior machines operate on the principle of sliding the wrapper over one or two straws, or sliding the straw or straws into the wrapper, and then sealing the ends of the wrapper. The wrappers are cut from a paper tube which is continuously formed in the machine from flat paper stock, and a supply of straws is stored in a hopper from which they are ejected in an orderly fashion. In one instance the straws are ejected from the hopper directly onto a conveyor which carries them to a station at which wrappers are slid over them, and in another instance the wrappers are placed on a conveyor, as they are cut from the paper tube, and carried to a station at which the ejected straws are slid into them. In either instance, the wrappers and enclosed straws are further carried by the conveyor past a station at which the wrapper ends are sealed, to a station where the completely packaged straws are ejected from the machine.

The present machine is of the type in which the straws are slid into the wrappers, and it is the primary aim and object of the present invention to provide a machine of this type which is simpler in construction, more reliable in operation, and capable of greater efficiency, than previous machines of this type.

Accordingly, it is a specific object of the present invention to provide a hopper in which a supply of straws is stored and from which straws are ejected unfailingly in an orderly fashion and with greater rapidity than was heretofore possible.

It is another specific object of the present invention to provide for the reliable placement of individual wrappers at heretofore unattainable speed onto a conveyor which, in turn, is indexed in unusually quick steps.

It is another specific object of the present invention to make provisions in the machine for rapidly and unfailingly sliding the ejected straws into the conveyed wrappers.

It is another specific object of the present invention to construct the machine so that the same is, despite its high operating speed, free from vibration and shock, and operating parts thereof are little subjected to wear.

2

The above and other objects, features and advantages of the present invention will be fully understood from the following description, considered in connection with the accompanying illustrative drawings.

In the drawings:

Fig. 1 illustrates diagrammatically the major steps performed by the present machine, from the formation of the paper wrappers to the completely packaged straws;

Fig. 2 is a fragmentary perspective view of the present machine;

Fig. 3 is another fragmentary perspective view of the machine as viewed in the direction of the arrow 3 in Fig. 2;

Fig. 4 is a close-up perspective view of a conveyor of the machine;

Fig. 5 is a plan view of the machine;

Fig. 6 is a side elevation of the machine as viewed in the direction of the arrow 6 in Fig. 5;

Fig. 7 is a plan view of a certain operating device of the machine;

Fig. 8 is a section taken substantially on the line 8—8 of Fig. 7;

Fig. 9 is a fragmentary section taken on the line 9—9 of Fig. 8;

Fig. 10 is an enlarged section taken on the line 10—10 of Fig. 5;

Fig. 11 is a section taken on the line 11—11 of Fig. 10;

Fig. 11A is an enlarged section taken on the line 11A—11A of Fig. 5;

Fig. 12 is an enlarged section taken on the line 12—12 of Fig. 5; and

Fig. 13 is a section taken on the line 13—13 of Fig. 8.

Briefly, the present machine performs the following major steps in forming wrappers and packaging straws therein. As indicated in Fig.

40 1, paper band 20 from a supply roll is formed continuously into a tube 22 having a "bonded" seam 24 longitudinally thereof. The seam 24 is formed in the tube 20 by intercrimping the overlapped side margins of the paper band 20.

45 Individual wrappers 26 of tubular form are then cut from the tube 22 and placed on a rotary conveyor which is indexed step-by-step so as to bring the wrappers 26 thereon successively to an assembly station at which one or more drinking straws 28, in the present instance two straws, are slid or injected into each aligned wrapper 26. The wrappers 26 and inserted straws 28 are then carried by the conveyor past a station at which the open ends of the wrappers are sealed

50 55 along the transverse seams 30 which, like the

seam 24, are formed by intercrimping the flattened wrapper ends. The sealed wrappers 26 with the inserted straws are thereupon ejected from the conveyor.

The present machine comprises a main base 34 on which the various operating mechanisms and devices of the machine are mounted. These mechanisms and devices are a wrapper forming mechanism A, a conveyor B, a conveyor indexing mechanism C, a straw supply hopper D, a straw transfer device E, and a wrapper sealing device F. These mechanisms and devices are hereinafter described in the order in which they are mentioned above.

Wrapper forming mechanism A

Referring to Figs. 5 and 6, the reference numeral 40 designates an arbor on which the paper tube 22 is formed. The arbor 40 is removably suspended from a bracket 42 through intermediation of spaced screws 44 which are screwed into tapped holes in the arbor 40. The bracket 42 is mounted on a housing 46 which is, in turn, mounted on the main base 34 of the machine. A paper band 20 from a supply roll 48 is passed between feed rolls 50 and led to the arbor 40 by a guide roll 52. The paper supply roll 48 is conveniently carried by a reel 54 which is suitably journaled on a pedestal 58, mounted at 58 on another housing 60 of the machine. One of the feed rolls 50, i. e., roll 50', is continuously power-driven, counter-clockwise as viewed in Fig. 6, by a suitable prime mover, such as an electric motor in the housing 60 and a suitable driving connection between the motor and the feed roll 50'. The companion feed roll 50" is journaled on a pivoted arm 64 which is urged by suitable spring means (not shown) in a clockwise direction as viewed in Fig. 6, thereby forcing roll 50" against roll 50'. For more positive feeding action, roll 50" is geared to roll 50' as at 66. The guide roll 52 is journaled on an arm 68 which is angularly adjustably mounted on the casing 60. As in prior machines of this type, the arbor 40 carries intermediate its ends a tube-forming sleeve 72 (Figs. 5, 11 and 11A) which is spaced from the arbor 40, except at its "point" attachment 74 to the latter. This "point" attachment may be accomplished by interposing a small spacer 76 between the arbor 40 and the sleeve 72 in the manner shown in Fig. 11A, and welding or otherwise securing these parts together. The paper band 20 is applied to the arbor 40 by sliding the leading end of the paper band into the space between the arbor 40 and the sleeve 72 in the manner shown in Fig. 11A, so that on subsequent power operation of the machine succeeding portions of the paper band will, while running along the arbor 40, and into the sleeve 72, be gradually turned into tubular shape. The gradually converging side margins of the paper band 20 thus move into overlapping relation with each other shortly after passing the point attachment 74 of the sleeve 72 on the arbor 40. The overlapping side margins of the tube 22 thus formed then pass between seaming rolls 78 and 80, the peripheries of which are provided with narrowly spaced indentations that compress the overlapped side margins of the tube into intercrimped or finely interfolded relation and thus "bond" them together along the seam 24. (Fig. 1.) The bond thus obtained along the seam 24 of the tube 22 is sufficiently strong for the purpose in mind. The seaming roll 80 (Fig. 11), is relatively small and is so journaled at 82 in the arbor 40 that its

indented periphery projects slightly above the periphery of the arbor, there to cooperate with the companion sealing roll 78. The companion roll 78 is mounted on a shaft 84 which is journaled at 86 in the housing 46 and carries within the latter a gear 88 which is in permanent mesh with another gear 90 on a counter shaft 92. Counter shaft 92 is journaled in a hub 94 of the housing 46 and a bearing bracket 95 on the machine base 34 (Fig. 5), and carries a sprocket 96 which is continuously driven from the motor in the housing 60 through a suitable driving connection, including a chain 98. Thus, the seaming roll 78 is continuously driven at a speed commensurate with that of the paper band 20, as it is fed by the feed rolls 50, and the seaming rolls 78 and 80 act also as additional feed rolls which advance the formed tube 22 between the cutting blades 100 of scissors 102 (Figs. 5 and 12).

The scissors 102 are operated at predetermined intervals, in a manner described herein-after, to cut tubular wrappers 26 of predetermined length from the tube 22 as the same is continuously formed and fed forward. The blades 100 of the scissors 102 are co-axially pivoted at 104 at the apex of a V-shaped member 106 (Fig. 12), the legs of which are mounted on parallel bars 108 (Fig. 10), which are slideable in the housing 46 for movement of the scissors 102 longitudinally of the paper tube 22, for a purpose hereinafter described. The blades 100 of the scissors 102 are provided with downward extensions 110 (Fig. 12) which carry anti-friction rollers 112 that cooperate with a cam 114 which is adapted to close the scissors for cutting wrappers 26 from the paper tube 22. The blades 100 of the scissors 102 are normally urged into closed or cutting relation with each other by a spring 116 which is anchored with its ends on pins 118 on the blade extensions 110, respectively. The cam 114 is, in the present instance, an angle which is carried by a lever 120 (Figs. 5 and 11). Lever 120 is mounted on a shaft 122 which is journaled in the housing 46 and carries on the inside of the latter an arm 123 with a follower 124 which cooperates with a cam disk 126 on the shaft 92 (see also Fig. 10). A spring 128 urges the follower 124 into permanent engagement with the cam disk 126. When the follower 124 cooperates with the outer periphery of the cam disk 126, as shown in Fig. 10, the cam 114 on the lever 120 is in the raised position shown in Fig. 12, in which it forces the blades 100 of the scissors 102 open. However, when the follower 124 cooperates with a depression 129 in the periphery of the cam disk 126, the cam 114 is sufficiently lowered from the position shown in Fig. 12 to permit the scissors to close and sever a wrapper 26 from the paper tube 22.

Also mounted on the shaft 92 is another cam disk 130 (Figs. 10 and 11), which cooperates with a follower 132 on a cross bar 134, secured at 136 to the bars 108. The follower 132 is normally urged by a spring 138 into engagement with the cam disk 130 under the control of which the scissors 102 are moved longitudinally of the paper tube 22, as described more fully hereinafter.

Conveyor B

As best shown in Fig. 6, there are mounted on the machine base 34 spaced upright brackets 140 which provide bearings 144 for a shaft 146 on which spaced identical wheels 148 are mounted. Shaft 146 and the wheels 148 thereon define a conveyor 149 for the paper wrappers 26 (Figs. 2,

4, and 6). Each wheel 148 is provided with a plurality of peripheral notches 150 for the reception of paper wrappers 26 in the manner shown in Figs. 2 and 4. The conveyor 149 is indexed step-by-step by mechanism described hereinafter, and wrappers 26 are placed, in a manner hereinafter described and during intermittent stops of the conveyor, in aligned notches 150 of the wheels 148. More particularly, the continuously forming and advancing paper tube 22 enters, during successive intermittent stops of the conveyor 149, aligned notches 150 in the conveyor wheels 148 of which successive ones align with the tube 22 on successive indexing steps of the conveyor. Every time the tube has advanced into aligned notches 150 in the conveyor wheels 148, the same is cut by the scissors 102 so as to leave a cut-off wrapper 26 on the conveyor wheels 148 on which it is then safely supported, but not yet correctly positioned thereon. The scissors 102 thereupon act, in a manner hereinafter described, to advance the wrapper further on the conveyor wheels 148 into correct disposition thereon.

Conveyor indexing mechanism C

As best shown in Figs. 2, 5 and 6, there is mounted on the conveyor shaft 146 a pin wheel 152 which is provided with as many equi-angularly spaced pins 154 as there are notches 150 in either conveyor wheel 148. Cooperating with the pin wheel 152 is a driver 156 on a shaft 158 which, as shown in Fig. 5, is journaled in bearing brackets 160 on the machine base 34. The driver 156 is provided with a peripheral flange 162, a portion 164 of which is gradually curved out of the plane of the flange 162 (Fig. 5) so as to provide in the latter a gap 166 of a width which is substantially equal to the diameter of any one of the pins 154. Also, the thickness of the flange 162 is preferably substantially equal to the gap between successive pins 154 so that the flange, which always projects between two successive pins 154 on the wheel 152, locks the latter against rotation in either direction, except when the same is indexed by the curved flange portion 164. When in the course of each revolution of the driver 156 in counter-clockwise direction as viewed in Fig. 6, the curved portion 164 of the flange 162 rides in the gap between two successive pins 154, the pin wheel 152 and the conveyor 149 are indexed through one step in clockwise direction as viewed in Fig. 2. As the curved flange portion 164 leaves the gap between successive pins 154, the adjacent flange end 162 enters the gap between the next successive pins 154, wherefore a portion of the flange 162 projects between successive pins 154 at all times and the rotation of the pin wheel 152 is under the permanent and sole control of the driver 156. Thus, the conveyor 149 is indexed one step during each revolution of the driver 156, and the flange 162 of the latter threads its way from pin to pin on the wheel 152 in order to lock the latter and the conveyor against rotation in either direction, except during the indexing thereof. Shaft 158 carries a helical gear 172 which is in permanent mesh with a companion gear 174, mounted on a shaft 176 which is journaled in suitable bearing brackets 178 on the machine base 34. Shaft 176 also carries a bevel gear 180 which is in permanent mesh with another bevel gear 182 on the adjacent end of the power-driven shaft 92.

Inasmuch as the paper wrappers 26 on the conveyor 149 are carried to certain stations, hereinafter described, at which they would drop from the conveyor by gravity, an arcuate guard 186 is

placed over each conveyor wheel 148 to prevent unauthorized gravity discharge of the wrappers 26 from the latter. The arcuate guards 186 are mounted on the adjacent brackets 140 through intermediation of bracket arms 188 (Figs. 2, 3 and 6). The guards 186 are omitted in Fig. 5, and only one guard is shown in Fig. 4, in order to expose certain structure which is normally hidden thereby.

10 As previously explained, the wrappers 26 are finally advanced by the scissors 102 on the conveyor into correct disposition thereon in which they engage or nearly engage, a stop 192 in the form of an arcuate plate, which is mounted at 15 194 on one of the brackets 140 (Figs. 2, 4, 5 and 6). There is also provided another stop 196 which is opposite the stop 192 and suitably suspended from the adjacent bracket arm 188 by a screw 198 (Figs. 2, 4 and 5). Thus, the wrappers 26 pass, 20 during a portion of their travel on the conveyor 149, between the stops 192 and 196 (Fig. 2), and are prevented by them from sliding from their correct disposition on the conveyor 149.

Straw supply hopper D

25 Mounted at 200 on a housing 202 on the machine base 34 is a bracket 206, having spaced ends 208 and a connecting L-shaped rib or web 210 (Figs. 7 and 9). Extending along the web 210 and between the ends 208 of the bracket 206 are two spaced plates 212 and 214 which project through a slot 216 in the top wall of the housing 202 and form a discharge gate 219 for a hopper 220 on the bracket 206. The hopper 220 contains a supply 30 of drinking straws 28 which are forced by gravity into the discharge gate 219. The discharge gate 219 is of such width as conveniently to hold a single column of superposed straws 28 in the manner shown in Fig. 9. Plate 212 is provided with 35 lateral end flanges 222 which are secured at 224 to the adjacent ends 208 of the bracket 206. The opposite plate 214 is secured with its lower end at 226 to a square bar 228 (Figs. 8, 9 and 13) which is rotatably carried by a rod 230, mounted 40 in the housing 202. The square bar 228 is connected with a vibrating mechanism to be described, whereby to vibrate the wall 214 of the discharge gate 219 for the purpose of agitating the straws 28 therein and prevent them from 45 becoming jammed. The wall 214 of the discharge gate 219 is, therefore, so loosely fitted between the ends 208 of the bracket 206 as to permit its vibration without interference from the bracket 206. The front wall 212 of the discharge gate 219 is apertured as at 232 (Figs. 3, 6 and 8) in 50 order to expose the straws 28 therein to full view and also gain immediate access to them in case they should become jammed after all.

The hopper 220 itself comprises opposite end 55 brackets 240 to which are secured at 242 the end walls 244 (Fig. 6) which may be of any suitable transparent plastic sheet material. Screwed or otherwise secured at 246 to the end walls 244 of the hopper are angles 248 (Figs. 5 and 6) to which the front and rear walls 252 and 254, respectively, of the hopper are secured as at 250. The front 60 and rear walls 252 and 254, which may be made of the same material as the end walls 244, preferably slant in the fashion shown in Fig. 2 in order to lead the straws in the hopper to the discharge gate 219 in the manner shown in Fig. 9. The hopper 220 is freely removable from the bracket 206, and normally rests thereon with its end brackets 240 in the manner shown in Figs. 2 and 6. The hopper 220 is accurately located on

the bracket 206 by means of pilot pins 256 on the latter which pass through holes in the end brackets 240 of the hopper.

For vibrating the wall 214 of the discharge gate 219 of the hopper 220, there is provided in the housing 202 a vibration cam 260 (Fig. 13) with which cooperates a follower 262 on a lever 264 (see also Fig. 8), which is journaled on a stub shaft 266, suitably mounted in the housing 202. Secured at 268 to the lever 264 is an arcuate link 270 which is preferably somewhat elastic and connected at 272 with a lateral extension 274 of the wall 214 of the discharge gate 219 (Fig. 13). The vibration cam 260, which is provided with a plurality of lobes 276, is mounted on a shaft 278 which is journaled near one end thereof in the housing 202 (Fig. 13), and near its other end in a bearing bracket 280 on the machine base 34 (Fig. 5). The outer end of shaft 278 carries a sprocket wheel 282 over which the previously mentioned chain 98 is passed, so that shaft 278 and the vibration cam 260 are driven from the chain 98. A spring 284 normally urges lever 264 counter-clockwise as viewed in Figs. 3 and 8, thereby forcing the follower 262 in permanent engagement with the vibration cam 260. Rotation of the cam 260 causes oscillation of the lever 264 at fairly high frequency and, due to the resiliency of the link 270, even faster oscillation of the wall 214 of the discharge gate 219 about the rod 280.

Straw transfer device E

As best shown in Fig. 9, the lower end of the front wall 212 of the discharge gate 219 is inwardly bent to form a ledge 286 on which the lowermost straw rests. The ledge 286 is spaced from the rear wall 214 of the discharge gate 219 to form a gap 288 in which a straw ejector bar 290 is movable. The ejector bar 290 is secured at 292 to a cross piece 294 (Figs. 8 and 13), which is mounted for sliding movement on parallel bars 296 in the housing 202. The cross piece 294 is provided with a longitudinal groove 298 (Fig. 13) in which is slidable a key 300 that is rotatably mounted on an extension 302 of one of the conventional link-joining pivots of a chain 304, which passes over sprocket wheels 306 and 308. Sprocket wheel 306 is mounted on the power-driven shaft 278, while the other sprocket 308 is freely rotatable on the stub shaft 266. Hence, the chain 304 is continuously driven when the machine is in operation, and reciprocates, through intermediation of the key 300, the cross piece 294 and the ejector bar 290 from and to the retracted position shown in Fig. 8. Thus, when the chain 304 is driven in the direction of the arrow 310 in Fig. 8, the ejector bar 290 will, during the passage of the key 300 along the upper run 304' of the chain 304, be advanced from the most retracted full line position to the most advanced position indicated by the dot-and-dash lines 290' (Fig. 8). During such advance movement of the ejector bar 290, the same engages the adjacent ends of the two lowermost straws 28 in the discharge gate 219 and slides the same longitudinally out of the discharge gate and through a funnel-shaped guide 312 into an aligned wrapper 26 on the conveyor 149. The ejector bar 290 is retracted into the full line position shown in Fig. 8 when the key 300 passes along the lower run 304'' of the chain 304, as will be readily understood. The cross piece 294 and ejector bar 290 have a harmonic motion during the passage of the key 300 around each sprocket 306 and 308, resulting in gradual

reversal of the movement of the reciprocating parts 294 and 290 in each direction. The guide 312 (Fig. 8) is carried by an arm 314 on a rod 316 which is longitudinally slidable in the housing 202 and carries a collar 318, having a peripheral groove 320 in which projects an anti-friction roller 322 on one arm of a bell crank lever 324. The bell crank lever 324 is pivoted at 326 on a lug 328 in the housing 202, and its other arm is provided with an inclined cam surface 330 which is adapted to cooperate with an anti-friction roller 332 on the cross piece 294. The bell crank lever 324 is normally urged by a spring 334 into a position in which the cam surface 330 thereof is in the path of the roller 332 (Fig. 3) and in which the guide-carrying bar 316 is in its most advanced position in which a stop collar 338 thereon engages the adjacent end wall 202a of the housing 202.

As stated above, the ejector bar 290 is adapted to remove the two lowermost straws 28 from the discharge gate 219 and slide them into an aligned wrapper 26 on the conveyor 149. Shortly after the ejector bar 290 advances from its most retracted position and before the leading ends of the two lowermost straws 28 in the discharge gate 219 enter the aligned wrapper 26 on the conveyor 149, the roller 332 on the cross piece 294 clears the cam surface 330 of the lever 324 and permits rod 316 to be spring-urged into its most advanced position in which the funnel-shaped guide 312 enters the adjacent open end of the aligned wrapper 26 (Fig. 3) for guiding the straws into the wrapper as they are ejected by the bar 290 from the discharge gate 219. The forward stroke of the ejector bar 290 is such as positively to advance the ejected straws into an aligned wrapper 26 on the conveyor until the straws are completely in the wrapper and spaced with their ends from the adjacent ends of the wrapper.

Inasmuch as the ejector bar 290 is reciprocated fairly rapidly and the straws are injected equally rapidly into the wrappers 26 on the conveyor 149, it is necessary to prevent the ejected straws from being carried, by their own inertia, with their leading ends to the adjacent ends of the wrappers where they would be crushed in the subsequent sealing operation of the wrapper ends. To this end, there is provided opposite the straw-ejection station S (Figs. 3, 4, 5 and 6) a device 360 which comprises cooperating prongs 362 and 364 of sheet metal that are mounted at 366 and 368, respectively, on the arcuate stop 192. These prongs 362 and 364 form a gradually narrowing passage P (Fig. 4) through which the adjacent ends of the wrappers 26 on the conveyor 149 travel as they approach and pass the station S, and in which these wrapper ends are substantially flattened, to such an extent that the injected straws are prevented from penetrating, by their own inertia, into these temporarily flattened wrapper ends.

Wrapper sealing device F

Journalled in bearings 340 on the brackets 140 (Figs. 5 and 6) is a shaft 342 which carries spaced pairs of cooperating seaming rolls 344 and 346 for forming the transverse seams 30 at the opposite ends of the straw-containing wrappers 26 on the conveyor 149. Shaft 342 is driven from a gear 343 on the pin wheel 152 which is in permanent mesh with a gear 345 on shaft 342. More particularly, the periphery of each seaming roll 344 and 346 is provided with nar-

rowly spaced indentations, the same as the previously described seaming rolls 78 and 80 that form the longitudinal seam 24 in the paper tube 22. The indented peripheries of each pair of associated rolls 344 and 346 firmly intercrimp the adjacent end of a wrapper 26 on the conveyor and form the transverse seam 30 as the wrapper is carried, during an indexing step of the conveyor past these rolls. Each of the rolls 346 is carried by a lever 348 (Fig. 12), which is pivotally mounted at 350 on the adjacent bracket 140 and is normally urged by a spring 352 in a direction to force roll 346 against the associated roll 344. The speed ratio between the gears 343 and 345 is such that each pair of associated seaming rolls 344 and 346 advances the adjacent end of a wrapper at substantially the same speed at which the latter moves with the conveyor during an indexing step thereof.

Mode of operation

When the machine is in operation, the feed rolls 50 and seaming rolls 78, 80 continuously draw paper from the supply roll 48 and form it into tubular shape on the arbor 40, sealing thereby the tube longitudinally along the seam 24 and continuously advancing the seamed tube 22 toward the conveyor 149. The leading end of the continuously forming and forwardly moving tube 22 advances, during an intermittent stop of the conveyor, into the then aligned notches 150' of the conveyor wheels 148 to the extent indicated in dot-and-dash lines in Fig. 4, whereupon the scissors 102, under the control of the cam disc 126 (Fig. 10), sever a wrapper 26 from the tube 22. At that time also, the closed scissors 102 are, under the control of the cam disk 130 (Fig. 10), moved from their most retracted position in the direction of the arrow 380 in Fig. 4 at a speed which is greater than the rate at which the tube 22 advances, whereby the wrapper 26, which was just cut off, is moved or pushed by the closed scissors 102 away from, and in advance of, the tube 22 into the longitudinal position 26'' on the conveyor 149 (Fig. 4). After the wrapper is advanced by the scissors 102 into the position 26'' on the conveyor 149, the latter is normally indexed one step into the position shown in Fig. 4, and the scissors 102, while continuing their forward motion at a considerably reduced rate of speed, however, in the direction of the arrow 380, are quickly opened under the control of the cam 126 (Fig. 10), bringing thereby the blade 100' of the open scissors into alignment with the wrapper which has now advanced to the position 26''' on the conveyor. The blade 100' of the continuously advancing scissors 102 then further advances the wrapper from the position 26''' on the conveyor at slow speed into the longitudinal position 26''', which is the correct disposition of the wrappers on the conveyor. The initial rapid, and continuing slower, forward motion, as well as the return motion, of the scissors 102 are under the control of the cam 130 which is designed to accomplish these scissor motions in correct timed relation with the operation of the rest of the machine. Thus, the correct placement of each wrapper 26 on the conveyor 149 is accomplished by the scissors 102 in two steps, the first step being rapid but of insufficient length to cause the wrapper to move into engagement with the stop 192 and possibly rebound therefrom, and the second step being slow and taking place during a time interval at which the tube 22 has not yet sufficiently ad-

vanced for cutting a wrapper therefrom. The scissors are, after each wrapper-positioning performance, retracted into position for cutting the next wrapper from the tube 22 which in the meantime has sufficiently advanced into the conveyor 149 to require cutting.

As shown in Fig. 5, the stop 192 is arranged in a slightly slanting manner so as to shift any slightly displaced wrapper or wrappers 26 on the conveyor into correct disposition thereon during the passage of the wrappers between the stops 192 and 196.

While the wrappers 26 on the conveyor are advanced step-by-step with the latter, they align successively and during intermittent stops of the conveyor with the funnel-shaped guide 312 at the assembly station S, where two straws are injected into each aligned wrapper in the previously described manner.

20 After the wrappers 26 on the conveyor 149 have received their straws at the assembly station S, they are, on continued indexing steps of the conveyor, carried with their ends between the opposite sets of end-seaming rolls 344, 346 by which 25 they are sealed along the seams 30. The wrappers, which are then completely sealed, are carried by the conveyor outside the region of the guards 186 where they descend by gravity onto spaced conveyor belts 390, each of which is passed over pulleys 392 and 394 (Fig. 5). The pulleys 392 are carried by the power-driven shaft 342, while the pulleys 394 are carried by a shaft 396 which is journaled in bearing brackets 398 on the machine base 34. The completely sealed 30 wrappers are thus carried by the conveyor belts 390 away from the conveyor 149 and over the machine base 34 to a place where they may conveniently drop into any suitable collector.

Having thus described my invention, what I claim and desire to secure by Letters Patent is:

40 1. In a machine for packaging drinking straws, having means for continuously feeding a paper tube axially, the combination of scissors having normally yieldingly closed, pivoted cutting blades 45 provided with followers positioned remote from said blades, respectively, and being reciprocable longitudinally of said tube and adapted on each reciprocation thereof to sever a length from the moving tube, means for reciprocating said scissors in timed relationship to the feed of said paper tube, and cam means to open said scissors comprising an angle movable from an inoperative position in to an operative position in which it extends longitudinally substantially parallel 50 to the direction of movement of said scissors and its legs engage said followers, respectively, to force said scissor blades apart for the reception 55 therebetween of said paper tube.

2. In a machine for packaging drinking straws, 60 having a conveyor with spaced holders in which tubular wrappers are axially insertable, means at a certain station for continuously feeding a paper tube axially into aligned holders on said conveyor, and a device intermittently advancing 65 said conveyor to bring successive holders thereof into alignment with said tube, the combination of scissors having normally closed cutting blades and being movable longitudinally of said tube into retracted, intermediate, and advanced positions, respectively, and mechanism operated in timed relation with said device for operating said scissors through a cycle during each step of said conveyor, said mechanism comprising first and second cam means for moving said scissors 70 and for opening the blades thereof, respectively,

11

said first and second cam means being so designed and operating during a cycle of said mechanism in such timed relation with each other as slowly to move the open scissors after an intermittent advance of said conveyor from an intermediate position to their advanced position with one cutting blade thereof in alignment with a previously inserted wrapper on the conveyor to push said wrapper from an intermediate position in its holder into final position therein while said tube 10 passes between said blades and approaches and enters an aligned holder on said conveyor, then to move the open scissors into their retracted position and there close them to cut a new wrapper from said tube, then rapidly to move the closed scissors to their intermediate position to push said new wrapper ahead of said tube into its intermediate position in its holder, and then immediately to open the scissors during the next intermittent advance of said conveyor.

3. The combination in a machine as set forth in claim 2, in which said scissor blades carry anti-friction rollers and are pivoted and normally

5

12

yieldingly urged into closed relation, and said second cam means includes an angle movable from an inoperative position into an operative position in which it extends longitudinally substantially parallel to the direction of movement of said scissors and its legs engage said rollers, respectively, and force said scissor blades apart.

SALVATORE A. FRANCO.
